CIRCUS-ACT-SIMULATING GAME TOY

John W. Ryan, Bel Air, Calif., assignor to Mattel, Inc., a corporation of California

Filed Feb. 1, 1966, Ser. No. 830

Term of patent 14 years

(Cl. D34—15)

FIG. 1 is a perspective view of a circus-act-simulating game toy showing my new design;

FIG. 2 is a rear elevational view of the structure shown in FIG. 1, and

FIG. 3 is a plan view of FIG. 2.

I claim:

The ornamental design for a circus-act-simulating game toy, as shown.
